CHARLES H. ROLLASON, OF WHEELING, WEST VIRGINIA, ASSIGNOR TO WHEELING STEEL CORPORATION, OF WHEELING, WEST VIRGINIA, A CORPORATION OF DELAWARE

REMOVABLE COVER FOR SHEET-METAL CONTAINERS

Application filed December 29, 1928. Serial No. 329,120.

This invention relates broadly to sheet metal barrels or drums, and more particularly to a removable cover for the heads of such containers.

5 The primary object of the invention is to provide a drum having a removable cover and provided with novel and practicable means for securing said cover in place.

Another object is to provide, in a device of 10 the character mentioned, a head and cover construction having associated therewith attaching means which may readily be rendered operative by means of a hammer.

Still another object is to provide a device 15 of the character mentioned which may be sealed so as to indicate unauthorized access to or tampering with the contents of the drum.

In describing my invention in detail, reference is had to the accompanying drawings, in which—

Figure 1 is a top plan view of a commercial form of sheet metal drum having a head and cover constructed in accordance with my invention;

Fig. 2 is a vertical section of the same;

Fig. 3 is a fragmentary section on line 3—3, Fig. 1.

Figures 4, 6 and 8 are fragmentary top plan views showing modifications of my invention; and

Figs. 5, 7 and 9 are vertical sections on lines 5—5 of Fig. 4, 7—7 of Fig. 6, and 9—9 of Fig. 8, respectively.

In said drawings, the numeral 1 indicates the body of a sheet metal container or drum and 2 the head for the same, said body and head being attached together, as by the usual double seam, as shown at 3. Said head has 40 therein a circular opening 4 through which the contents may be introduced and removed, and defining said opening is an upstanding flange 5 which may have its terminal edge turned outwardly and downwardly, as shown at 6.

The opening 4 is closed by a disk-like sheet metal cover 7 which has therein an upwardly pressed circular rib 8 presenting a downwardly facing channel adapted to receive 50 therein the upstanding flange 5 of the head.

In order to seal said opening, a rubber or cork gasket 10 is inserted between the head and cover, as within the channel of the rib 8.

Attached to the head, as by welding, intermediate the seam 3 and the flange 5 are the 55 oppositely disposed foot portions 11^a of a plurality of vertically disposed sheet metal tongues 11 which, when the cover 7 is placed upon said head, protrude through slits 12 provided in the adjacent portions of said 60 cover in registering relation to said tongues. Said tongues are formed by doubling upon itself the metal between said foot portions, as shown. Said slits are preferably reinforced by having their edges outwardly beaded, as 65 indicated at 13. After said cover is placed upon said head with the tongues 11 protruding through the slits 12, as aforesaid, it is secured in place by bending the protruding tongues 11 laterally over the beads 13 of said 70 slits, as shown in dotted lines in Fig. 3.

It is preferred that in forming the head it be pressed inwardly, as shown, to a sufficient depth that no part of the head structure, when assembled and fastened, will extend beyond the upper extremities of the seam 3, so that said head structure will be less liable to injury from rough handling of the 75 drum.

In the modification shown in Figs. 4 and 5, the tongues 11' instead of being formed of a doubled strip of sheet metal, are formed of wire in the shape of a loop and the terminals of the wire are turned in opposite directions to form foot portions which are 80 welded to the head 2; and, when the cover 7 is in place, said loop may be bent laterally over the adjacent bead 13, as shown in dotted lines in Fig. 4.

In the modifications illustrated in Figs. 6 85 to 9, inclusive, an open wire ring 14 is passed through the eyes formed in the tongues 11'' and 11''', respectively, and has its ends secured to each other by a seal (not shown), 90 after which said loops are flattened upon the cover, as shown in dotted lines in Figs. 7 and 9, as by means of a hammer, to secure the cover tightly in place. As will be understood, the condition of the seal of the wire 95 ring will readily reveal to a receiver of a 100

transported or stored drum whether the cover has been removed after sealing.

What is claimed is—

1. A sheet metal drum having a head with an opening provided therein, said opening being defined by an upstanding flange, a cover for said opening having formed therein a channel adapted to receive said flange, a seating gasket received within said channel, said cover having an annular horizontal flange having therein a series of slits, and means for removably securing said cover to said head, said means comprising tongues carried by said head and adapted to protrude through said slits and to be bent downward into binding relation to said cover.
2. A sheet metal drum having a head with an opening provided therein, said opening being defined by an upstanding flange, a plurality of upright members carried by said head, a cover for said head having a channel formed therein designed to register with said flange and having a horizontal annular flange, a gasket received within said channel, said cover also having slits formed in its flange in registering relation to said upright members so that when said cover is placed upon said head said members will protrude through said slits and may thereupon be bent downwardly over said cover for securing the latter in seated relation to said head.
3. In a sheet metal drum having a head with an opening therein, a cover for said opening having an annular portion which occupies seated relation to said head and which has therein a plurality of apertures, and members carried by said head in protruding relation to said apertures, said members being adapted to have their protruding ends severally interengaged for preventing withdrawal of the cover.
4. In a sheet metal drum having a head with an opening therein, a cover for said opening having an annular portion which occupies seated relation to said head and which has therein a plurality of apertures, and upright members carried by said head in protruding relation to said apertures, said members being adapted to have their protruding ends severally interengaged with said annular portion of the cover for preventing withdrawal of the latter.

In testimony whereof, I affix my signature.
CHARLES H. ROLLASON.
